Patented Dec. 16, 1919.

FIG. 1

FIG. 2

inventor
Joseph H. Pickareck
by his Attorney
Clifford D. D.

UNITED STATES PATENT OFFICE.

JOSEPH H. PICKARECK, OF DETROIT, MICHIGAN, ASSIGNOR TO DETROIT FUSE AND MANUFACTURING COMPANY, OF DETROIT, MICHIGAN, A CORPORATION OF MICHIGAN.

ELECTRICAL SWITCH.

1,325,042.

Specification of Letters Patent. Patented Dec. 16, 1919.

Application filed May 12, 1916. Serial No. 96,967.

To all whom it may concern:

Be it known that I, JOSEPH H. PICKARECK, a citizen of the United States, residing in the city of Detroit, county of Wayne, and 5 State of Michigan, have invented certain new and useful Improvements in Electrical Switches, of which the following, taken in connection with the accompanying drawings, is a full, clear, and concise description 10 thereof.

This invention relates to electrical switches of the knife-blade type and has for its object the provision of simplified and inexpensive means for connecting a pair of 15 pivoted knife-blade contacts, so that they may be operated in unison and maintained in parallel relation and in perfect alinement with the coöperating jaw contacts. The means provided for this purpose comprises 20 a cross-head or connecting member of insulating material preferably of rectangular outline having its ends or extremities reduced in thickness and received within apertures provided in the knife-blade contacts, 25 the latter being provided with suitable projections, which project through corresponding apertures formed in the cross-head and riveted over to securely retain both blades and cross-head in rigid operable connection.

30 In the accompanying drawings, I have illustrated one preferable embodiment of the invention,

Figure 1 being a perspective view of a switch mechanism of the protected type embodying the invention, and Fig. 2 an enlarged detail in perspective.

The knife-blade contacts are indicated by the numeral 1. These are pivotally mounted at 2 to supports 3, which are in electrical 40 connection with the binding posts 4. The free ends of the knife-blade contacts 1 co-operate with the jaw contacts 5, which in turn are electrically connected with the binding posts 6 through the fuse holders 7.

45 The knife blade contacts at a point preferably adjacent to the free ends thereof are notched or cut away as at 8 leaving intermediate projecting tongues or lugs 9 which coöperate with the ends of the insulating 50 cross-head 10. This cross-head may have its extremities reduced in cross-section and is provided with rectangular apertures for the reception of the tongues or lugs 9. The reduced ends of the cross-head extend below 55 the upper edge of the knife-blade contacts,

as clearly shown in Fig. 2, so that suitable apertured metal washers or plates 11 may be placed over the top of the lugs 9, the latter being then riveted thereupon to securely fasten and rigidly connect the cross-head with the knife-blade contacts. The thickened portion of the cross-head intermediate the reduced ends fits snugly against the knife-blade contacts as at 12, thus forming shoulders which aid in holding the 60 knife-blade contacts properly spaced and also adds the desired rigidity to the structure as a whole. The cross-head is provided centrally with a connecting member 13, which has operable connection with a crank 65 14 by means of which the mechanism is operated. By connecting the operating member 14 with the cross-head at a point substantially intermediate the knife-blade 70 contacts, a balanced pull upon the knife-blade 75 contacts is effected when the mechanism is operated to make or break the electrical circuit.

While I have illustrated and described one preferable structure in which my invention may find embodiment, I do so by way of example only as changes may be resorted to without departing from the spirit and scope of my invention as defined by the following claims.

Having thus described my invention, what I claim as new herein and desire to secure by Letters Patent, is:—

1. In an electrical switch, in combination, a pair of spaced knife-blade contacts, a pair 90 of coöperating spaced jaw contacts and a crosshead of insulating material connecting said knife-blade contacts, each of said contacts having two portions cut away to provide an intermediate lug, said crosshead being apertured near its ends to receive said lugs, the ends of the crosshead fitting within the cut away portions of the knife blades, each lug being passed through an aperture and the lugs being riveted over the crosshead 95 to prevent separation of parts.

2. In a switch of the character described, the combination of a pair of pivoted knife-blade contacts, a pair of coöperating jaw contacts, a cross-head connecting the knife-blade contacts and fastening means therefor comprising a lug along a longitudinal edge of each of the knife-blade contacts, extending through the cross-head and riveted there-over to prevent separation of the parts. 110

3. In a two-pole switch of the character described, a pair of pivoted knife-blade contacts, a pair of fixed coöperating jaw contacts, a connecting member extending across 5 and joining the knife-blade contacts to move them in unison, said knife-blade contacts being provided with fastening lugs and apertures on their longitudinal edges for receiving the ends of the connecting member, said 10 lugs being riveted over the top of the connecting member to hold it in position.
4. In an electrical switch of the character described, the combination of a pair of pivoted knife-blade contacts, a pair of spaced 15 coöperating jaw contacts and a cross-head connecting the knife-blade contacts whereby the latter are kept in parallel relation and in alinement with the jaw contacts and fastening means for connecting the cross-head to 20 the knife-blade contacts including an integral lug along a longitudinal edge of each of the knife-blade contacts, extending through suitable apertures in the extremities of the cross-head, washers positioned upon the cross-head and held in place by the riveting of the extremities of the lugs of the knife-blades upon the washers. 25
5. In an electrical switch of the character described, the combination of a plurality of spaced knife blades having recesses in their longitudinal edges, and lugs formed intermediate said recesses, of a cross head having apertures therein to receive said lugs, and reduced portions fitting within said recesses, said lugs passing completely through 30 said cross head and being riveted at their ends. 35
6. A blank for a knife blade electric switch, comprising a flat rectangular strip of metal which is provided near one end with means for pivotally mounting the strip, said strip having two notches or cut-out portions along one longitudinal edge thereof to provide an intermediate lug for attaching a crosshead. 40

JOSEPH H. PICKARECK.
